JEROME A. PAQUETTE, OF ST. LOUIS, MISSOURI.

CIGARETTE-CASE.

1,188,199.

Specification of Letters Patent. Patented June 20, 1916.

Application filed March 25, 1915. Serial No. 16,886.

To all whom it may concern:

Be it known that I, JEROME A. PAQUETTE, citizen of the United States, residing at St. Louis, State of Missouri, have invented certain new and useful Improvements in Cigarette-Cases, of which the following is a full, clear, and exact description, reference being had to the accompanying drawings, forming a part hereof.

10 My invention has relation to improvements in cigarette cases; and it consists in the novel features of construction more fully set forth in the specification and pointed out in the claim.

15 The object of my invention is to provide a cigarette case from which the cigarettes may be discharged one at a time by a proper manipulation of the movable sections comprising the case.

20 A further object is to provide a case which shall be simple, positive in its action, light, and durable; and one possessing other advantages better apparent from a detailed description of the invention in connection 25 with the accompanying drawings, in which—

Figure 1 is a plan of the case with parts broken away to expose the interior; Fig. 2 is a similar view showing the sections of the 30 case moved the necessary degree to effect the discharge of the terminal cigarette of the series confined in the case; Fig. 3 is a bottom end view of the case looking up toward Fig. 1, parts being broken away; Fig. 4 is a 35 view of the delivery end of the case, being a projection of Fig. 1 turned one hundred and eighty (180) degrees; Fig. 5 is a transverse section on the line 5—5 of Fig. 1 showing the case preparatory to effecting a 40 discharge of a cigarette; and Fig. 6 is an inside plan view of the holder member or that which carries the cigarettes, the retracting spring being severed at a point intermediate its length.

45 Referring to the drawings, 1 represents a box-like holder or container having an outer wall α , an inner abbreviated opposite parallel wall b , side walls c , c' , a bottom wall d , and an upper lip or flange e , one 50 end of which is removed or cut away so as to leave a free passage-way or recess r for the discharge of the cigarette m . To the bottom of the inside of the wall e is riveted or otherwise secured one end of a strip 2, 55 which carries a pin p at a point removed a suitable distance from the riveted end of

the strip, said pin having coupled thereto the inner end of a coiled contracting spring 4 whose outer end is secured to the upper terminal wall h of the sliding lid or cover 60 3, the wall h being provided with a marginal lip or flange t , which, together with the flange u of one of the side walls w of the lid, and the abbreviated flange u' of the opposite side wall w' of the lid, serves to 65 form a telescoping connection between the lid and the holder. Any equivalent construction for effecting such telescoping or movable connection however is contemplated by my invention. The upper wall 70 h of the lid is provided with an opening O opposite the recess r for the free passage of the terminal cigarette of the series confined in the case. The base of the wall w of the lid, opposite the discharge opening O is 75 provided with a lip, tongue or platform or equivalent supporting member 5 normally engaging the bottom wall d of the holder or container when the container is closed; that is to say, when the members 1 and 3 are 80 drawn together under the action of the contracting spring 4. To readily slide the lid along the holder, the latter is preferably provided with a thumb bearing 6, and the lid with a finger bearing 7 as shown, the 85 arrows in Fig. 5 indicating the relative movement to which the members 1 and 3 are subjected to effect the discharge of a cigarette.

Secured by the same rivet 8 which secures 90 the strip 2 to the wall e of the holder, is the adjacent end of a spring arm 9 whose opposite end is riveted to the outer end of a similar spring arm 10 diverging therefrom, the inner end of the last arm being 95 secured to the adjacent terminal of a bearing strip or follower 11, said follower being normally disposed in parallelism with the side walls of the case, whereas the spring arms 9, 10, are normally divergent, spreading apart toward the bottom of the case. The cigarettes are interposed between the follower strip 11 and the opposing wall c' of the holder, which wall by the way is abbreviated so as to terminate at the free edge 105 of the wall b , thereby leaving an opening A for ready access to the terminal cigarette of the series, so that said cigarette may be lifted and initially adjusted over the platform 5 for purposes of ejection when the 110 case is subsequently operated. This initial adjustment is sometimes necessary, espe-

cially when the case is first filled with cigarettes and before any have been discharged.

The operation is substantially as follows: By sliding the lid 3 sufficiently to cause the flange u' to clear the wall a of the holder, the latter may be withdrawn from under the flange u and sufficiently separated from the lid (remaining connected thereto however by the spring 4 which readily stretches 5) when the members 1 and 3 are thus separated) to permit the holder to be filled with cigarettes. These are placed in sufficient number between the follower strip 11 and the opposing wall c' , the advancing springs 10 or members 9, 10, closing or contracting, to a degree depending on the number of cigarettes charged into the case. When properly charged, the lid and holder are reassembled by inserting first one side of the holder 15 behind the flange u of the lid, and then passing the opposite side behind the flange u' , and when subsequently released, the spring 4 will automatically draw the holder into the lid, or what amounts to the same thing, will 20 draw the lid over the holder and close the case. To make sure that the first cigarette of the series is over the platform 5, the smoker in first filling the case inserts his finger through the slot or opening A (provided 25 for the accommodation of the platform 5) and raises the end cigarette if necessary sufficiently to insure its being directly over said platform when the holder and lid are assembled in the manner described. The 30 case is now charged for dispensing the cigarettes one at a time. The smoker by seizing the case between his thumb and forefinger (Fig. 5) and separating the lid from the holder, that is to say, sliding the lid to open 35 position along the holder (Fig. 2) causes the cigarette which is directly over the platform 5 to become separated from the main body of cigarettes stored in the holder 1, the cigarette thus separated (Fig. 2) being directly 40 in line with the recess r and the discharging opening O. When the lid and holder are allowed to contract or close (under the contracting action of the spring 4) the main charge of cigarettes are pushed 45 back in the case toward the top wall h of the lid; but in so returning to their original position, they force the cigarette which is on the platform 5, out of the opening O, sufficiently 50 to permit the protruding end of the cigarette thus projected, to be seized by the smoker, and withdrawn completely from the case. This being done, the next succeeding cigarette of the series is forced into 55 position over the platform 5 by the feed or dilating action of the advancing springs 9, 60 10, and like its predecessor is now in posi-

tion to be discharged or projected from the case in the same manner. The friction between the main body of cigarettes and the cigarette on the platform 5 is sufficient to cause said cigarette to be pushed out of the case when the members 1 and 3 are drawn back to their normally closed or contracted position. 65

The specific manner here shown for effecting the telescopic connection between the holder and lid; or the specific springs here illustrated for restoring or contracting the members when once dilated or expanded, or for advancing or feeding the charge of cigarettes; or the specific follower here shown, and other details shown and described need not be adhered to, as the device is susceptible of many changes without departing from the nature or spirit of my invention. 70

Obviously the invention is not to be considered as restricted to dispensing cigarettes, but may be applied to other articles. The lid or cover need not of course absolutely conceal the contents of the package from 75 view, the term "lid" or "cover" being here used to designate any member complementary to the holder proper to form therewith a complete case. 80

Having described my invention what I claim is:

A cigarette dispensing case comprising a holder having an outer wall, an inner abbreviated wall, bounding side walls, a bottom wall, an upper inwardly-turned lip, a lid having an upper flanged wall, and side flanged walls for receiving the holder, an inwardly bent platform at one end of one of the side walls of the lid adapted to rest on the bottom of the holder to receive in succession the cigarettes charged into the holder, the top wall of the lid having a discharge opening opposite the platform, a coiled contracting spring having its ends respectively coupled to the top wall of the lid at the end removed from the discharge opening, and to the adjacent side wall of the holder, a feed or advancing spring in the holder having a pair of diverging arms one of which is secured to the side wall of the holder adjacent the point of connection of the contracting spring therewith, a follower carried by the free end of the opposite arm for engaging the cigarettes and forcing them toward the platform carried by the lid, the parts operating substantially as set forth. 100

In testimony whereof I affix my signature, in presence of two witnesses.

JEROME A. PAQUETTE.
